UNITED STATES PATENT OFFICE.

ADOLPH FRIEDRICH, OF NEW YORK, N. Y.

AMUSEMENT DEVICE.

Application filed September 26, 1921. Serial No. 503,239.

To all whom it may concern:

Be it known that I, ADOLPH FRIEDRICH, a citizen of the United States, residing at New York city, N. Y., have invented certain new and useful Improvements in Amusement Devices, of which the following is a clear, full, and exact description.

My invention relates to an amusement device of novel design not only in the mechanical combinations involved, but also novel in its outward aspect as well. To this end I have utilized the legend of Jack and the bean stalk and provided a mechanical figure representing Jack in the act of ascending a bean stalk to escape a giant who is lying with open mouth prone at its base.

My device may be used singly or several devices, alike in structure and design, may be arranged side by side.

20 In the use of my device I so arrange the mechanism that by rolling a ball into the giant's mouth, Jack will be made to ascend the bean stalk by intermittent stages, one stage or jump each time a ball goes into the giant's mouth. If a ball fails to enter the mouth, Jack does not move.

With the elements of the device coordinated as suggested, various and numerous modes of operation may be employed. For 30 instance as a game of contest, each player will roll the number of balls necessary to get Jack to safety at the top of the bean stalk, and the one employing the fewest balls wins. Or when several devices are arranged together, each player will have his own device and all will start to roll at the same time and the one getting Jack to the top of the bean stalk first will win. In the one case the number of balls employed is 35 the determining factor, while in the other case the time element is controlling.

I have also provided for using any one or more of the devices as a game in which a score is indicated, and to do this I have arranged a removable indicator which may be attached to or removed from the bean stalk and when attached thereto will indicate the several positions Jack assumes during his climb.

50 To carry out the spirit of the legend more completely the giant is made to move his head and eyes each time Jack reaches a new height.

With the principles and general plan stated, the details of mechanical construction whereby the purposes of the invention

are accomplished, also various novel combinations of parts and mechanisms, together with other features and advantages of the invention, will become apparent from a consideration of the following detailed description taken in connection with the accompanying drawings, in which—

Fig. 1 is a front elevational view of my device showing the base in section; 65

Fig. 2 is a longitudinal sectional view;

Fig. 3 is a section taken on the line 3—3 of Fig. 2;

Fig. 4 is a part sectional, part elevational view taken on the line 4—4 of Fig. 3; 70

Fig. 5 is a view taken on the line 5—5 of Fig. 3;

Fig. 6 is a fragmentary detail of the movable tooth of the actuating ratchet wheel looking in the direction of the arrows in Fig. 7, which latter figure is an elevation of the fragment in Fig. 6 as viewed from below; 75

Fig. 8 is a detail of the element representing a beanstalk; 80

Fig. 9 is a side view of the tappets which are used to give movement to the feet and legs of Jack;

Fig. 10 is a section on the line 10—10 of Fig. 1; 85

Fig. 11 is a detail of the mechanism for moving the giant's eyes;

Fig. 12 is a detail of the arrangement for returning the balls;

Fig. 13 is a view similar to Fig. 8, but 90 with the detachable score indicator in place; and

Fig. 14 is a wiring diagram.

Referring to the drawings, a base member 1 of suitable width and length is provided with a runway 2 along which a number of balls may be rolled. The base member 1 has its sides projecting above the runway 2 to prevent the balls from rolling off as indicated in Fig. 100

1. At the rear of the runway is a representation of a giant's head formed preferably of easily molded material properly supported by a framework and pivoted to the base member at 3. The base member is also provided with a guide portion 4, Fig. 2, 105 which directs the ball after it enters the mouth so that it follows a path to make contact at 5 with spring fingers which act to close an electric circuit to actuate the mechanism to cause Jack to ascend the bean stalk, 110 the detail of which mechanism will be later described. The ball follows the path indi-

cated at Fig. 2 dropping to the bottom of the base member where it may be diverted as desired. Any balls which fail to enter the giant's mouth may follow a path such as indicated by the balls 6 and 7 in Fig. 3, these balls also dropping into the bottom of the base member to be diverted as desired.

Suitably secured to the base member is an upright member 8 having tappets 9 and 10 on its face as indicated in Figs. 1, 8 and 13, said member being of suitable width and slotted about midway thereof. This member is made to represent a portion of a beanstalk, the effect being that it rises from the rear of the giant's head as though the giant were reclining against it. At the top the member 8 has projecting rearwardly therefrom an arm 11 which carries a journal 12 for a pulley 13 over which passes a sprocket chain 14. The base member carries a journal 15 rigidly supported therein and on which is a sprocket wheel 16 having teeth at suitable distances to engage the sprocket chain. The journal 15 also carries a pinion 17 with which engages a toothed wheel 18 secured to a shaft 19, to which is also secured an actuating ratchet wheel 20 having fixed teeth 21 and a single pivoted tooth 22, Figs. 4, 6, and 7, the fixed teeth and the single movable tooth numbering together eight teeth. The number of teeth in the gear 18 and pinion 17 is such that one-eighth movement of the ratchet wheel 20 will cause the sprocket wheel 16 to move a distance between two of its teeth and move the sprocket chain accordingly.

The sprocket chain is adapted to move adjacent the inside of the slot in the member 8, representing the beanstalk, and projecting outwardly through this slot are fingers supporting the body of Jack, who is represented by the numeral 23. Each of these fingers is formed of wires bent as at 24, and shown most clearly in Fig. 10. The figure representing Jack includes arms individually pivoted at 25 and legs pivoted at 26 and 27 and both the feet and hands are adapted to engage the alternate tappets 9 and 10 of the member 8 as Jack moves up, giving the effect of climbing, the legs of Jack being normally raised to the position of the upper leg shown in Fig. 9. As Jack moves upwardly from the position shown in Fig. 9, to the position shown in Fig. 2, the tappet 10, Fig. 9, will engage the top of the foot and depress the leg against the tension of a spring 28, Fig. 2, until Jack reaches the position there depicted when the foot will slip off of the tappet and again rise to the position shown to have been assumed by one of the legs in Fig. 9. Similar movement of the arms will also take place.

The ratchet wheel 20 is adapted to be actuated by means of a weighted pawl 30 pivoted at 31 to a link 32 which in turn is

pivoted at 33 to the end of the armature 34 of a solenoid 35. The link 32 has also pivoted to it at 31 a lever 36 which in turn is pivoted on the shaft 19. Normally Jack is in the position shown in Figs. 1, 2 and 9 near the base of the beanstalk, and movable tooth 22 is positioned as shown in Fig. 4 with the weighted pawl 30 ready to engage it when the solenoid is energized, the tooth 22 being also weighted so that it normally assumes the position shown in this figure.

The circuit from the solenoid 35 is normally open at the contacts 5 beyond the opening of the giant's mouth, as shown in Fig. 2, and when any ball enters the mouth it closes said contacts thereby causing energization of the magnet 35 and a consequent movement of Jack up the beanstalk. If it be assumed that three balls, for instance, are sufficient to enable Jack to reach the top of the beanstalk, it will then be desirable to return him to normal position. This is accomplished by providing a manual switch for closing the circuit through the solenoid 35 to cause Jack to move down behind the beanstalk around the sprocket wheel 16 and back to normal position at the base of the beanstalk. For this purpose it will be noted that in Fig. 2 the bottom of the base member is apertured at 37. When, however, Jack has reached normal position, it is desirable that no further movement take place except through the medium of a ball rolled into the giant's mouth, and to insure that he shall not be moved beyond normal position, means are provided for rendering the actuating means ineffective to move Jack further under control of the manual switch. To this end a magnet 38 is provided and the ratchet wheel 20 is provided with a contact member 39, Fig. 4, which bridges terminals 40 and 41 conveniently supported at the base 42 of the solenoid 35, these contacts being situated in a circuit including the magnet 38. The manually operable switch 105 also is included in this circuit and the contact member 39 is so situated that when the movable tooth 22 reaches the position shown in Fig. 4, the contacts 40 and 41 are bridged and the circuit through the magnet 38 is closed if the manual switch is in proper position. The magnet then moves an armature 43 connected to the movable tooth 22, drawing the tooth inwardly to the position shown in Fig. 6, wherein it is out of the path of the pawl 30, so that any further movement of the pawl due to energization of the solenoid 35 will have no effect to move Jack from his position at the base of the beanstalk.

In order to give the proper effect, it is contemplated that the giant's head shall also move simultaneously with Jack up the beanstalk and to accomplish this, the head is pivoted as described at the point 3 and at 130

the rear portion of the framing supporting the head, as at 44, Fig. 4, is connected the core 45 of a solenoid 46, which is connected in the same circuit including the contacts 5 so that whenever the solenoid 35 is energized to move Jack, the solenoid 46 is also energized to move the giant's head, this movement being a slight rocking movement. Simultaneously with this movement the eyes 10 of the giant are made to move, this being accomplished by the mechanism shown in Figs. 2 and 11. The eyes are supported by a wire having a central portion 48 and offset end portions 49 which pass through each 15 eye 50 forming the pivot upon which the eyes may move, the end portions 49 being supported by portion 51 formed integral with or attached to the giant's head and necessarily moving with the same when the 20 solenoid 46 is energized to rock the head. A link 52 connects the main portion of the wire 48 with the stationary guide 4 so that as the head moves about the pivot 3 the effect is a pull on the rod 52 which has the effect 25 of rotating the eyes and giving the effect of looking upwardly towards Jack as he climbs the bean stalk.

As suggested in the earlier part of the description, the device or devices of the invention may be used in various ways, and one way suggested is that of a contest device in which a score is indicated. When, however, it is not desired to indicate a score the scoring device is made removable. This device is in the form of a scale 53, Fig. 13, adapted to be fastened to the member 8 by thumb nuts 54 and provided with numerals 0, 1, 2 and 3.

The operation of my device either used 40 singly or in combination with a number of other similar devices will be more readily understood by a consideration of Fig. 14 showing the way the circuits are arranged. In this figure the wires 55 and 56 are the 45 main lead wires to which current may be supplied from any suitable source indicated at 57, the line switch 58 being normally closed. When a ball is rolled into the giant's mouth the contacts 5 are closed, the circuit 50 then flowing from the wire 55, to the point 59, wire 60, to contacts 5, to wire 61, to solenoid 35, to solenoid 46, to wire 62, back to the point 63 at the other side of the line. The ratchet wheel will thus be moved one 55 step each time the circuit is closed at 5 and the giant's head will be rocked, these operations being controlled by the solenoids 35 and 46 respectively.

The circuit above traced is for the device 60 represented by A. If a second device B is provided the solenoids 35 and 46 are connected in parallel, the current flowing from the point 64 of wire 55 along wire 65, to contacts 5, wire 66, to solenoid 35 and thence 65 to solenoid 46 and through wire 67 to the

other side of the line at 68. Similarly the solenoids 35 and 46 of a third device C are energized. When, however, Jack has reached the top of the bean stalk by reason of the fact that at least three balls have 70 entered the giant's mouth and made contacts at the terminals 5, and it is desired to return Jack to normal position, the manually operable switch 70 is actuated. This switch is controlled by a rod 71 bent 75 as shown in Fig. 14, said rod controlling a second switch 72. When the rod 71 is moved inwardly, the switch 72 is first closed and a moment later the switch 70. Closing of the switch 70 permits current to flow 80 from the wire 55, through the switch 70, to the wire 74, wire 75, to the points 76, 77 and 78 and through the solenoids 35 and 46 and through wires 79, 67 and 62 back to the other side of the line. By moving 85 the rod 71 back and forth a succession of times, the solenoids 35 act to move Jack around to normal position and when normal position is reached, it is desired that further closing of the switch 70 will have 90 no effect. It will be remembered that when Jack reaches normal position the ratchet wheel 20 is in such a position that its contact 39 bridges the contacts 40 and 41. These contacts are shown in Fig. 14 as being 95 connected each to a wire 80 terminating at the point 81 so that when the switch 72 is closed the magnet 38 will be energized in each device only when the ratchet wheel 20 of that device reaches normal position and when the magnet 38 is so actuated the movable tooth 22 of the ratchet wheel is pulled in so that further movements of the pawl 30 are ineffective to cause 100 any movement of the ratchet wheel. Just 105 as soon, however, as the switch 72 is opened the tooth 20 drops by the weight of its connected armature to normal position ready to be actuated by the pawl 30. By reason of the fact that the contact 72 is closed before contact 70 any movement of the rod 71 after Jack reaches normal position will 110 result in the contact 72 being first closed and consequently the tooth 22 will be withdrawn from normal position prior to the 115 closing of the switch 70 and therefore prior to the supplying of current to the solenoid 35. As soon, however, as a ball is rolled into the giant's mouth, the contact piece 39 moves away from the contacts 40 and 41 120 opening the circuit through the magnet 38 at this point so that thereafter closing of the switch 72 will have no effect on the magnet 38 until the ratchet wheel 20 again reaches normal position. The magnets 38 125 are each connected to a wire 82 to carry the current from the switch 72 to the other side of the line.

In some cases it may be desired to give 130 a signal that Jack has reached the top of

the bean stalk and for this purpose contacts 83 are shown, these contacts acting to close a circuit which controls a signal device 84 of any suitable character.

5 While I have shown my invention as most conveniently embodied in figures representing Jack, the beanstalk and the giant, it will be understood that variations may be resorted to within the scope of the invention without departing from the spirit thereof.

What I claim as new is:

1. An amusement device, representing Jack-and-the-bean-stalk, in combination, a figure representing Jack, a representation of a bean stalk, a representation of a giant's head with open mouth, and means situated beyond the mouth and adapted to be actuated by a ball, rolled into the mouth, to cause Jack to ascend the bean stalk.

2. An amusement device, representing Jack-and-the-bean-stalk, in combination, a figure representing Jack, a representation of a bean stalk, a representation of a giant's head with open mouth, and means situated beyond the mouth and adapted to be actuated by a ball rolled into the mouth to cause Jack to intermittently ascend the bean stalk as successive balls are rolled into the mouth.

3. An amusement device, representing Jack-and-the-bean-stalk, in combination, a figure representing Jack, a representation of a bean stalk, a representation of a giant's head with open mouth, and means situated beyond the mouth and adapted to be actuated by a ball rolled into the mouth to cause Jack to ascend the bean stalk and the giant to roll his eyes.

4. An amusement device, representing Jack-and-the-bean-stalk, in combination, a figure representing Jack, a representation of a bean stalk, means actuated by a ball to cause Jack to ascend the bean stalk by intermittent movement until he reaches the top thereof, said intermittent movement taking place each time a ball follows a particular path, and means actuated at will to return Jack to the starting point at the base of the beanstalk.

5. An amusement device representing Jack-and-the-bean-stalk, in combination, a figure representing Jack, a representation of a bean stalk, means actuated by a ball to cause Jack to ascend the bean stalk by intermittent movement, until he reaches the top thereof, said intermittent movement taking place each time a ball follows a particular path, means actuated at will to return Jack to initial position and for then rendering the actuating means ineffective.

6. An amusement device representing Jack-and-the-bean-stalk, in combination, a

figure representing Jack, a representation of a bean stalk, means actuated by a ball to cause Jack to ascend the bean stalk by intermittent movement, until he reaches the top thereof, said intermittent movement taking place each time a ball follows a particular path, manually controlled means for returning Jack to initial position, and means for rendering the actuating means ineffective to move Jack by the manually controlled means while permitting the actuating means to function under control of a ball.

7. An amusement device representing Jack-and-the-bean-stalk, in combination, a figure representing Jack, a representation of a bean stalk, means to move Jack intermittently, including a ratchet wheel having fixed teeth and a pivoted tooth, a pawl for actuating the ratchet wheel, and means for withdrawing the pivoted tooth from the path of the pawl when Jack reaches a predetermined position in respect of the bean stalk.

8. An amusement device representing Jack-and-the-bean-stalk, in combination, a figure representing Jack, a representation of a bean stalk, means to move Jack intermittently, including a ratchet wheel having fixed teeth and a pivoted tooth, a pawl for actuating the ratchet wheel, a solenoid for moving said ball, and a circuit for said solenoid adapted to be closed by a ball following a particular path.

9. An amusement device representing Jack-and-the-bean-stalk, in combination, a figure representing Jack, a representation of a bean stalk, a representation of a giant's head with open mouth, means actuated by a ball rolled into the giant's mouth to cause Jack to ascend the bean stalk one step at a time, said means including a ratchet wheel, a pawl for said ratchet wheel, a solenoid for moving said pawl, and a circuit for said solenoid having contacts situated beyond the mouth opening to be closed by a ball entering the mouth.

10. An amusement device representing Jack-and-the-bean-stalk, in combination, a figure representing Jack, a representation of a bean stalk, a representation of a giant's head with open mouth, means actuated by a ball rolled into the giant's mouth to cause Jack to ascend the beanstalk one step each time a ball enters the mouth and a scale to measure the movements of Jack when the device is operated one way, said scale being detachable to provide for operating the device another way.

Signed at New York city this 22nd day of September 1921.

ADOLPH FRIEDRICH.
